GRAPH

Theodore H. Beard and Joseph M. Lucarelle,
Bridgeport, Conn., and William J. O'Neil, Atlantic
Beach, N. Y., assignors to Dictaphone Corporation, New York, N. Y., a corporation of New York

Application November 26, 1940, Serial No. 96,826

Term of patent 14 years

To all whom it may concern:

Be it known that we, Theodore H. Beard, a citizen of the United States and a resident of Bridgeport, in the county of Fairfield and State of Connecticut, and Joseph M. Lucarelle, a citizen of the United States and a resident of Bridgeport, in the county of Fairfield and State of Connecticut, and William J. O'Neil, a citizen of the United States and a resident of Atlantic Beach, in the county of Nassau and State of New York, have invented a new, original, and ornamental Design for a Combined Supporting Base and Cover for a Desk Phonograph, of which the following is the specification, reference being had to the accompanying drawing, forming part thereof.

The dominant features of our design reside in the portion shown in full lines.

We claim:

The ornamental design for a combined supporting base and cover for a desk phonograph, substantially as shown and described.
